[57] CLAIM

The ornamental design for a gas turbine fan blade, as shown.

DESCRIPTION

FIG. 1 is a perspective view taken from the top, rear and left side of a gas turbine fan blade showing my new design.

FIG. 2 is a right side elevational view thereof, with a center portion being broken away for convenience of illustration.

FIG. 3 is a top plan view thereof.

FIG. 4 is a bottom plan view thereof.

FIG. 1

FIG. 2

FIG. 3

FIG. 4
